(57) **CLAIM**

The ornamental design for a display screen with graphical user interface, as shown and described.

DESCRIPTION

The single view in the drawing is a front view of a display screen with graphical user interface.

The broken lines showing of a display screen illustrate environment and form no part of the claimed design. The broken line showing of the graphical user interface illustrates portions of the article and form no part of the claimed design.

1 Claim, 1 Drawing Sheet
